PREPARATION OF N-SUBSTITUTED HYDRAZINE DERIVATIVES

David W. Lum and Irving L. Mador, Cincinnati, Ohio, assignors to National Distillers and Chemical Corporation, New York, N.Y., a corporation of Virginia

No Drawing. Application September 23, 1957
Serial No. 685,416

5 Claims. (Cl. 260—583)

This invention relates to a method for preparing derivatives of hydrazine. More particularly, the invention pertains to a process for producing hydrazines having N-substituted acyclic or cyclic hydrocarbon groups.

Recent interest in the use of hydrazine derivatives in the field of jet propulsion and for the preparation of various nitrogen-containing compounds has led to a search for a method of preparing hydrazine derivatives which is capable of being employed on a commercial scale. The processes proposed heretofore have involved either expensive reactants or elaborate reaction and recovery steps.

One object of the present invention is to provide a commercially attractive process for the preparation of hydrazine derivatives. Another object of the invention is to provide a process which avoids the difficulties of the prior art processes and at the same time results in high yields of hydrazine derivatives. Further objects of the invention will become apparent from the ensuing description.

In accordance with the invention, it has been found that various derivatives of hydrazine may be prepared by reaction of substituted urea with alkaline hypochlorite under certain carefully controlled conditions. Though the reaction of urea with alkaline hypochlorite to produce hydrazine has been used commercially for a number of years, the operating conditions differ from those required in the process of this invention. For example, the instant process does not require the use of inhibitory agents such as gelatin, glue, glycerine, etc. The reactions involved in the process of this invention are represented by the following equations:

wherein R is an acyclic or cyclic hydrocarbon radical having from about 1 to 18, preferably about 1 to 8, carbon atoms. More specifically, R may be a straight or branched chain alkyl radical, having from about 1 to 18 carbon atoms, such as methyl, ethyl, propyl, isopropyl, butyl, isobutyl, hexyl, heptyl, octyl, isooctyl, decyl, dodecyl, and etc. The alkyl radical may also contain such functional groups as hydroxyl, ether and any other group which does not interfere in the reaction. When hydrazine derivatives having a cyclic substituent are desired R may be either cycloalkyl, aryl, alkaryl or heterocyclic radicals such as cyclopropyl, cyclobutyl, cyclohexyl, cyclooctyl, phenyl, tolyl, xylol, phenyl methyl, phenyl ethyl, furyl, pyridyl, pyrryl, thiophenyl, etc. As will be seen from the above equations, the R substituent in the hydrazine derivative product will correspond to the R substituent in the substituted urea employed as the feed material. In general, alkyl or aryl mono-substituted ureas, e.g. methylurea and phenylurea, are the preferred feed material.

The substituted ureas capable of being employed as the starting material in the process of this invention may be obtained from any known source. For example, Belgian Patent No. 450,541 indicates that methylurea may be pro-

2

duced by the direct reaction of methylamine and urea under pressure. Other possible methods for producing methylurea include refluxing a mixture of methylamine hydrochloride with an excess of urea or by the reaction of alkali cyanates with methylamine. As will be understood, the method of preparing the substituted urea feed does not constitute an essential feature of this invention.

In addition to the particular reactants employed, the present invention also involves carrying out the reaction under controlled operating conditions. To begin with, the temperature at which the reactants are initially mixed has been found to be critical. In general, it has been discovered that the reactants, should be mixed at temperatures within the range of about -5° C. to 20° C. , preferably about 0° C. to 5° C. In preparing alkyl mono-substituted hydrazines, for example, best results were obtained when separate aqueous solutions of sodium hydroxide and alkyl urea were mixed with the subsequent addition of a cold sodium hypochlorite solution. The reaction mixture is then heated to a temperature of about 10° C. to 100° C. , preferably about 60° C. to 100° C. , and held at this elevated temperature for about $\frac{1}{2}$ to 2 hours to complete the reaction. If, on the other hand, the reactants were mixed at elevated temperatures, i.e. about 60° C. to 80° C. , little or no hydrazine derivative was produced regardless of the order of mixing. It has also been found that if the mixed cold reactants are allowed to stand for a prolonged period of time before being heated to the reaction temperature, noticeably reduced yields of the hydrazine derivatives are obtained.

The exact reaction temperature employed will, of course, depend upon the particular reactants involved. As set forth above, the reaction temperature may vary from about 10° C. to 100° C. , the high temperature being somewhat preferred for the preparation of certain derivatives such as the alkyl mono-substituted hydrazine. When aryl substituted hydrazines are being prepared, lower reaction temperatures are sufficient for the rearrangement reaction. Thus, for example, the reaction of phenylurea with sodium hypochlorite will take place below 20° C.

Though at least two moles of sodium hydroxide are required for each mole of substituted urea employed, in practice it was found that good results were obtained when from about 3 to 10 moles of sodium hydroxide were used for each mole of substituted urea. Even when the mole ratio was 20 to 1 yields as high as 48 percent were achieved, while maximum yields were obtained at a mole ratio of about 8 to 1. The sodium hypochlorite solution can have a concentration in the range of about 3 to 20 percent, though a range of 5 to 15 percent is preferred. The mole ratio of sodium hypochlorite to substituted urea will generally be about 1:1. Though an excess of sodium hypochlorite was found to be beneficial in obtaining high yields, its presence was found to be somewhat detrimental during recovery of the hydrazine derivative product by distillation. More particularly, it was found that excess sodium hypochlorite would destroy some of the hydrazine derivative product. It is necessary, therefore, to destroy or otherwise remove the excess of sodium hypochlorite from the reaction product mixture prior to distillation. One method found to be effective was the addition of materials such as sodium thiosulfate, or sodium sulfite to the reaction product mixture to destroy the excess sodium hypochlorite. Other methods for removing excess sodium hypochlorite may also be employed. It is also within the scope of this invention to carefully control the excess of sodium hypochlorite employed in the reaction, e.g. about 5 to 25 percent, so that the usual side reactions would completely utilize the initial excess of this reactant.

The invention will be more fully understood by reference to the following illustrative examples:

Example I

Methylurea 2 g. (0.0270 mole) and 6.5 g. sodium hydroxide (0.163 mole) were each dissolved in 10 ml. of water, mixed and cooled to less than 5° C. Then 50 ml. of 5.17 percent sodium hypochlorite solution (0.0350 mole) was also cooled to less than 5° C. and added. This mixture was then heated to 80° C. over a period of about 20 minutes and maintained at 80° C. for one hour. At the end of this period the reaction mixture was cooled, diluted to 100 ml. and titrated with standard potassium iodate. Indicated yield was 0.0191 mole methylhydrazine or 70 percent of theory based on methylurea used. Methylhydrazine was identified as the sulfate (M.P. 141-142° C.) and picrate (M.P. 166° C.). Literature values for these melting points are 142° C. and 166° C., respectively.

Example II

20. g. of methylurea (0.270 mole) was dissolved in 50 ml. of water and cooled to less than 5° C. To this was added 80 g. of sodium hydroxide (2.0 moles) dissolved in 150 ml. of water and again cooled. To the above mixture 500 ml. of cold 5.17 percent sodium hypochlorite solution (0.350 mole) was added. On mixing the reactants were heated to 80° C. for one hour, cooled to room temperature and an aliquot titrated with standard potassium iodate. The indicated yield of methylhydrazine was 0.198 mole or 73 percent based on starting methylurea.

The reaction mixture was distilled without destroying excess hypochlorite. The first 50 ml. of distillate was set aside and the product in the remainder precipitated as the sulfate by adding an excess of sulfuric acid and reducing to a syrup. Hydrazine sulfate was recovered by dissolving the syrup in a minimum of water and then adding sufficient concentrated sulfuric acid to make the solution approximately 30% in sulfuric. After filtering of the insoluble hydrazine sulfate, the methyl hydrazine sulfate was precipitated by adding 8 volumes of ethanol:

Hydrazine sulfate 0.92 gm., 2.9%; M.P. 248-250° C.
Methylhydrazine sulfate 11.4 gm., 33%; M.P. 140-142° C.

Example III

0.75 gm. of phenylurea (0.0055 mole) was dissolved in 25 ml. of ethanol, cooled to 2° C. and 20 ml. of cold 10 percent aqueous sodium hydroxide added. Then 7.0 ml. of cold 5.17 percent sodium hypochlorite (0.0049 mole) was added, the reactants mixed and permitted to

warm up to room temperature. On titration with standard potassium iodate a yield of 0.00091 mole phenylhydrazine was indicated, or 18 percent based on hypochlorite used. The phenylhydrazine was identified by isolation of the cinnamaldehyde derivative, M.P. 167-168° C. This melting point in the literature is 168° C.

5 The above data show that substituted hydrazines may be prepared readily in accordance with the process of this invention. It will be understood that the substituted hydrazines may be separated from the reaction product mixture by such conventional methods as distillation, final dehydration with caustic, etc. Other hypochlorites such as t-butyl hypochlorite may also be employed in the reaction. The choice of solvents employed will depend, of course, upon their chemical stability and boiling point as well as their solubility properties.

10 While particular embodiments of the invention are shown above, it will be understood that the invention is obviously subject to variance and modification within the 20 scope of the above description and the following appended claims.

What is claimed is:

1. A method of preparing hydrazine derivatives having the formula

25 wherein R is an alkyl group having from 1 to 18 carbon atoms, which comprises mixing a mono-substituted urea having the formula

30 wherein R is said alkyl group, with sodium hypochlorite and sodium hydroxide at a reduced temperature of about -5° to 20° C., immediately allowing the resulting reaction to proceed at a temperature of about 10° to 100° C. to produce said hydrazine derivatives.

35 2. The method of claim 1 wherein R is an alkyl group having from 1 to 8 carbon atoms.

3. The method of claim 1 wherein said mono-substituted urea is methylurea.

40 4. The method of claim 1 wherein said reduced temperature is about 0° to 5° C.

5. The method of claim 1 wherein an excess amount of sodium hypochlorite is employed, and excess sodium hypochlorite in the resulting reaction product mixture is

45 converted to a non-deleterious form by reaction with sodium thiosulfate.
